SIGNALING SYSTEM

John Ellis Ostline, Chicago, Ill., assignor to Associated Electric Laboratories, Inc., Chicago, Ill., a corporation of Delaware

Application August 2, 1941, Serial No. 405,155

18 Claims. (Cl. 179—18)

The present invention relates to signaling systems and more particularly to improved switching apparatus for automatic telephone systems.

An automatic telephone system conventionally comprises switching apparatus including a selector having access to ten groups of trunks respectively terminated in the ten levels in the associated terminal bank. Also, a selector of this character may be rendered access to a larger number of trunk groups by splitting one or more levels in the associated terminal bank, whereby each of the split levels terminates two separate trunk groups.

While split level selectors of the character mentioned are entirely satisfactory in operation, they conventionally comprise dual access trunks or wiper sets, including dual test wipers, for purpose of selective control in conjunction with the split levels in the associated terminal bank, thereby rendering such selectors more complicated, both in mechanical construction and electrical connection, than is desirable.

Accordingly, it is an object of the present invention to provide an improved selector of the type mentioned, which is of simple construction and connection and which is economical to manufacture and thoroughly reliable in operation.

Another object of the invention is to provide an improved selector of the split level type, which comprises a single access trunk and a wiper set including a single test wiper.

A further object of the invention is to provide a telephone system comprising improved switching apparatus for setting up connections between the various subscriber substations and between the subscriber substations and the service operator positions, in a simple and efficient manner.

A further and more specific object of the invention is to provide an improved selector of the split level type, which comprises a simple and reliable mechanism for selectively controlling the operation thereof to select idle trunks in the two groups terminated in each split level in the associated terminal bank.

Further features of the invention pertain to the particular arrangement of the mechanical elements of the selector and of the circuit elements of the telephone system, whereby the above-outlined and additional operating features are attained.

The novel features believed to be characteristic of the invention are set forth with particularity in the appended claims. The invention, both as to its organization and method of

operation, together with further objects and advantages thereof, will best be understood by reference to the following specification taken in connection with the accompanying drawings, in which Figs. 1 and 2, taken together, illustrate diagrammatically a telephone system embodying the present invention; Fig. 3 is a fragmentary plan view of a portion of the switching mechanism incorporated in a selector embodying the present invention; Fig. 4 is a fragmentary side elevational view of the portion of the switching mechanism shown in Fig. 3; Fig. 5 is a further fragmentary side elevational view of the portion of the switching mechanism mentioned; and Fig. 6 illustrates diagrammatically a switch spring assembly incorporated in the switching mechanism.

Referring now more particularly to Figs. 1 and 2 of the drawings, there is shown a telephone system, including an exchange serving a plurality of subscriber substations T₁, T₂, etc., and including switching apparatus and operator position equipment. More particularly, a plurality of subscriber lines 101, 230, etc., respectively extend to the subscriber substations T₁, T₂, etc., and terminate in the switching apparatus at the exchange. More specifically, each subscriber line terminates in a line switch individual thereto included in the switching apparatus, the subscriber lines 101 and 230 respectively terminating in the line switches 102 and 231. The operator position equipment provided in the exchange comprises a manual operator position 0, a toll operator position 110, an information operator position 113 and a miscellaneous operator position 112.

The switching apparatus provided at the exchange comprises, in addition to the line switches 102, 231, etc., a plurality of selectors 100, etc., a group of special service selectors 233, etc., and ten groups of connectors, the connector 232 being included in the tenth group.

Each of the subscriber substations T₁, etc., comprises conventional substation equipment including a telephone instrument, a ringer and a calling device; while each of the operator positions 0, 110, etc., is provided with conventional operator position equipment. Each of the line switches 102, etc., is of conventional connection and arrangement. Also, each of the special service-selectors 233, etc., is of the conventional drop-back Strowger type; while each of the connectors 232, etc., is of the conventional Strowger type. Finally, the various trunks extending to the different operator positions 0, 110, etc., are

provided with conventional trunk circuits, not shown.

Preferably, each of the selectors is identical to the selector 100 which comprises a switching mechanism 170, a relay group including a switch-through relay R110, a line relay R120, a hold relay R130, a transfer relay R140, a step relay R150 and a prefix relay R160, and a control network. The switching mechanism 170 is of the drop-back Strowger type, including a wiper shaft 171 carrying three wipers 172, 173 and 174, and an associated semicylindrical contact bank 175. The contact bank 175 comprises ten vertical levels of contact sets, each level of contact sets including ten circumferentially spaced-apart individual contact sets. Also, the switching mechanism 170 comprises a vertical magnet M176 for driving the wiper shaft 171 in the vertical direction, a rotary magnet M177 for driving the wiper shaft 171 in the rotary direction, and a release magnet M179 for releasing the wiper shaft 171 and for causing it to be returned to its normal rotary and vertical positions.

Two sets of switch springs S180 and S181 are associated with the wiper shaft 171 and controlled by the movement thereof away from its normal vertical position; three sets of switch springs S188, S191 and S194 are associated with the wiper shaft 171 and controlled by the movement thereof away from its normal rotary position eleven steps in the rotary direction; two sets of switch springs S182 and S183 are associated with the wiper shaft 171 and controlled by the movement thereof away from its normal vertical position a predetermined number of steps in the vertical direction; and one set of switch springs S184 is associated with the wiper shaft 171 and controlled by the movement thereof away from its normal rotary position a predetermined number of steps in the rotary direction only when the wiper shaft 171 has been previously moved in the vertical direction predetermined numbers of steps and corresponding to certain levels of the associated contact bank 175, as explained more fully hereinafter.

Considering now the trunking arrangement of the telephone system, it is noted that the line switch 102 individually associated with the subscriber line 101 has access to a number of trunks 105, etc., individually extending to the selectors 100, etc.; the connector 232 included in the tenth group has access to one hundred subscriber lines including the subscriber line 230; and the special service selector 233 has access to three groups of trunks respectively including the trunks 234, 235 and 236 respectively extending to the toll operator position 110, the information operator position 113 and the miscellaneous operator position 112. The first five contact sets in the first level in the contact bank 175 of the switching mechanism 170 incorporated in the selector 100 individually terminate five trunks 211, etc., respectively extending to five connectors included in the first group; while the last five contact sets in the first level in the contact bank 175 individually terminate five trunks 216, etc., respectively extending to five special service selectors, the trunk 216 extending to the special service selector 233. Also, the first seven contact sets in the tenth level in the contact bank 175 individually terminate seven trunks 201, etc., respectively extending to seven connectors included in the tenth group, the trunk 207 extending to the connector 232 in the group mentioned;

while the last three contact sets in the tenth level in the contact bank 175 individually terminate three trunks 208, etc., respectively extending to the manual operator position 0. Finally,

5 the ten contact sets in each of the levels from the second through the ninth levels in the contact bank 175 individually terminate ten trunks respectively extending to ten connectors included in the groups from the second to the ninth, inclusive.

10 Referring now more particularly to Figs. 3 to 6, inclusive, of the drawings, there is shown in greater detail a portion of the switching mechanism 170 incorporated in the selector 100. This 15 portion of the switching mechanism 170 comprises the wiper shaft 171 previously mentioned, the wiper shaft 171 being mounted in suitable bearings, not shown, for both step-by-step movement in the vertical direction and step-by-step 20 movement in the rotary direction. Also, the wiper shaft 171 carries a vertical ratchet 301 which cooperates with a drive pawl, not shown, which is driven by the vertical magnet M176, and a rotary ratchet 302 which cooperates with 25 a drive pawl, not shown, which is driven by the rotary magnet M177. Also, a vertical retaining pawl, not shown, cooperates with the vertical ratchet 301 and a rotary retaining pawl, not shown, cooperates with the rotary ratchet 302,

30 the last-mentioned pawls being operatively associated with the release magnet M179. Further, this portion of the switching mechanism 170 comprises a switch spring assembly, including first and second sections, the first section of 35 the switch spring assembly including the switch springs 185, 186 and 187 and the second section of the switch spring assembly including the switch springs 189, 190, 192, 193, 195, 196 and 197.

40 Further, the wiper shaft 171 carries a substantially U-shaped bracket 303 provided with two spaced-apart arms 304 and 305, the wiper shaft 171 extending through aligned holes provided in the arms 304 and 305. The bracket 303 is retained in place on the wiper shaft 171 by two screws 306 and 307 respectively arranged in tapped holes provided in the arms 304 and 305, the ends of the screws 306 and 307 engaging the cylindrical outer surface of the wiper shaft 171.

45 Finally, the wiper shaft 171 carries one or more slotted cams 310, two cams 310 being illustrated. Each of the cams 310 has an elongated slot 311 formed therein, which extends from the center to the periphery thereof. The cams 310 are disposed between the arms 304 and 305 of the bracket 303, the slot 311 provided in each of the cams 310 straddling the wiper shaft 171. Each of the cams 310 is retained or clamped in place upon the wiper shaft 171 by an arrangement including a screw 312 extending across the slot 311 formed 50 therein. The screw 312 extends through an opening formed in the body of the cam 310 disposed on one side of the slot 312 and the end thereof is threaded into a tapped hole provided in the body of the cam 310 disposed on the opposite side of the slot 311, whereby the body portions of the cam 310 disposed on the opposite sides of the slot 311 may be forced toward each other by the screw 312 into gripping relation with the outer cylindrical surface of the wiper shaft 171. This gripping action of the body portions of the cam 310 disposed on the opposite sides of the wiper shaft 171 is facilitated by a narrow slit 313 formed in the body portion of the cam 310 in alignment with the slot 311.

55 60 65 70 75

The bracket 303 and the various cams 310 carried by the wiper shaft 171 are disposed adjacent the switch spring assembly and cooperate with a roller 314 carried on the outer end of the switch spring 186. More particularly, the roller 314 is arranged between two inwardly disposed and spaced-apart arms 315 carried on the outer end of the switch spring 186 and mounted upon a pin 316 extending between the arms 315. Each of the cams 310 comprises a first cylindrical cam surface 317 of a relatively small radius disposed in noncooperating relationship with respect to the roller 314, and a second cylindrical cam surface 318 of a relatively large radius disposed in cooperating relationship with respect to the roller 314; while the leading edge of the bracket 303 is provided with a cylindrical cam surface 319 arranged exteriorly of the second cam surface 318 of the cam 310 and disposed in cooperating relationship with respect to the roller 314.

Finally, the outer surface of the portion of the wiper shaft 171 disposed between the arms 304 and 305 of the bracket 303 carries indicia in the form of the numerals 1 to 0, inclusive, which is utilized for reference purpose in locating the vertical positions of the various cams 310 carried by the wiper shaft 171 with respect to the vertical steps thereof, as explained more fully below. Similarly, the upper surface of each of the cams 310 carries indicia in the form of the numerals 1 to 0, inclusive, which is utilized for reference purpose in locating the rotary position of the cam carried by the wiper shaft 171 with respect to the rotary steps thereof, as explained more fully below. In the present example, two cams 310 are carried by the portion of the wiper shaft 171 disposed between the arms 304 and 305 of the bracket 303; the upper cam 310 being positioned adjacent the numeral 1 of the indicia mentioned and cooperating with the roller 314 in the first vertical step of the wiper shaft 171, and the lower cam 310 being positioned adjacent the numeral 0 of the indicia mentioned and cooperating with the roller 314 in the tenth vertical step of the wiper shaft 171.

When the wiper shaft 171 occupies both its normal vertical and rotary positions the upper cam 310 is disposed one step below the roller 314; and the first cam portion 317 of each cam 310 is disposed in radial alignment with respect to the roller 314. Accordingly, when the wiper shaft 171 is moved step by step in the vertical direction the upper cam 310 is brought into the plane of the roller 314 upon the first vertical step and the lower cam 310 is brought into the plane of the roller 314 upon the tenth vertical step. Subsequently, when the wiper shaft 171 is moved step by step in the rotary clockwise direction the upper cam 310 or the lower cam 310, respectively, cooperates with the roller 314 only in the event the wiper shaft 171 respectively occupies its first or tenth vertical step at this time. Assuming that the wiper shaft 171 has been previously driven one step in the vertical direction when the step-by-step movement in the rotary clockwise direction thereof is initiated, the second cam surface 318 of the upper cam 310 will engage the roller 314 upon some rotary step, depending upon the adjusted position of the upper cam 310 with respect to the wiper shaft 171. It will be apparent that by shifting the rotary position of the upper cam 310 with respect to the wiper shaft 171, as indicated by the position of the indicia mentioned with respect to the leading edge of the cam surface 319 provided on the bracket 303, the

second cam surface 318 of the upper cam 310 may be adjusted to engage the roller 314 at any rotary step. In the illustrated example, the numeral 1 of the indicia mentioned, carried by the upper surface of the upper cam 310, is arranged in alignment with the leading edge of the cam surface 319 of the bracket 303 due to the adjustment of the upper cam 310 with respect to the wiper shaft 171; accordingly, in the illustrated example, when the wiper shaft 171 is driven one step in the rotary clockwise direction the second cam surface 318 of the upper cam 310 engages the roller 314.

When the roller 314 is thus engaged by the second cam surface 318 of the upper cam 310 the movable switch spring 186 is moved out of engagement with the stationary switch spring 185 and into engagement with the stationary switch spring 187. Subsequently, when the wiper shaft 171 is driven eleven steps in the rotary clockwise direction, and regardless of the vertical stepped position thereof, the cam surface 319 of the bracket 303 engages the roller 314. When the roller 314 is thus engaged by the cam surface 319 of the bracket 303 the movable switch spring 186 is moved out of engagement with the stationary switch spring 185 and into engagement with the stationary switch spring 187, in the event this operation has not previously occurred. Further, at this time, the movable switch spring 186 engages an insulator 320 carried by the switch springs 189, 192 and 195. When the insulator 320 is thus engaged the switch springs 189, 190 and 192, 193 are respectively moved into disengagement; then the switch springs 195 and 196 are moved into engagement; and, finally, the switch springs 196 and 197 are moved into disengagement, as clearly shown in Fig. 6.

In view of the foregoing explanation of the mode of operation of the portion of the switching mechanism 170 shown in Figs. 3 to 6, inclusive, of the drawings, it will be understood that, by appropriately adjusting both the vertical and rotary positions of one or more cams 310 carried by the wiper shaft 171, the roller 314 may be operated in order to govern the switch springs 185, 186 and 187 at one or more variable operated positions of the switching mechanism 170, each variable operated position of the switching mechanism comprising any predetermined vertical step and any predetermined rotary step of the wiper shaft 171 which may be desired. Further, it will be understood that in the switching mechanism 170 the roller 314 will be operated by the bracket 303 when the wiper shaft 171 is moved eleven steps away from its normal rotary position, regardless of the previous vertically stepped position of the wiper shaft 171 away from its normal vertical position.

The operation of the switching mechanism 170 incorporated in the selector 100, as well as the general connection and arrangement of the system, will best be understood from a consideration of the following description, with reference to Figs. 1 and 2 of the drawings, of the operation of the apparatus incorporated therein to set up the different connections between the various subscriber substations and between a subscriber substation and the various operator positions.

Considering now the extension of a call from a subscriber substation, such, for example, as the subscriber substation T1 connected to the subscriber line 101, to another subscriber substation, such, for example, as the subscriber substation T2 connected to the subscriber line 230, the call

is first initiated at the calling subscriber substation T1 by removing the receiver of the telephone instrument thereat from its associated switchhook. When the call is thus initiated at the calling subscriber substation T1 the line switch 102 individually connected to the subscriber line 101 operates in order to hunt for a trunk extending to an idle selector in the associated group. Assuming that the selector 100 is the first idle selector in the group accessible to the line switch 102, the line switch mentioned operates to seize the trunk 105, the trunk 105 individually extending to the selector 100 and being marked as idle by the absence of ground potential upon the control conductor C108 thereof.

When the trunk 105 is thus seized by the line switch 102 a loop circuit is completed between the line relay R120 in the selector 100 and the calling subscriber substation T1. This loop circuit extends from ground by way of the switch springs 197 and 196 of the set of switch springs S194, the lower winding of R120 and the contacts 113 to the line conductor C107 of the trunk 105, and from battery by way of the upper winding of R120 and the contacts 111 to the line conductor C106 of the trunk 105, the line conductors C106 and C107 of the trunk 105 being connected by way of the line switch 102 and the line conductors of the subscriber line 101 to the calling subscriber substation T1. When this loop circuit is completed the upper and lower windings of the line relay R120 are energized, thereby to cause the latter relay to operate. Upon operating, the line relay R120 completes, at the contacts 121, an obvious circuit, including the contacts 117, for energizing the winding of the hold relay R130, thereby to cause the latter relay to operate. Upon operating, the hold relay R130 completes, at the contacts 131, an obvious path for applying ground potential to the control conductor C108 of the trunk 105 in order to retain the line switch 102 in its operated position and to mark the subscriber line 101 extending to the calling subscriber substation T1 as busy to the connectors having access thereto.

At this time, the subscriber at the calling subscriber substation T1 dials the directory number of the called subscriber substation T2 which, in the present example, is 20XX, this number comprising the prefix digit 2, the digit 0 identifying the group of connectors, including the connector 232, having access to the subscriber line 230 extending to the called subscriber substation T2, and the digits XX identifying the vertical and rotary positions of the contact set terminating the subscriber line 230 appearing before the various connectors in the group mentioned. The line relay R120 follows the impulses of the prefix digit 2, restoring each time the loop circuit mentioned is interrupted and operating each time the loop circuit mentioned is recompleted. Each time the line relay R120 restores it completes, at the contacts 122, a circuit, including the contacts 117 and 133, for energizing in series the winding of the transfer relay R140 and the vertical magnet M176, and interrupts, at the contacts 121, the previously traced circuit for energizing the winding of the hold relay R130. Each time the line relay R120 operates it completes, at the contacts 121, the previously traced circuit for energizing the winding of the hold relay R130, and interrupts, at the contacts 122, the previously traced circuit for energizing in series the winding of the transfer relay R140 and the vertical magnet M176. When the transfer relay R140 is thus energized

it operates; and each time the vertical magnet M176 is thus energized it operates in order to drive the wiper shaft 171 of the switching mechanism 170 one step in the vertical direction. Both the hold relay R130 and the transfer relay R140 are of the slow-to-release type. Accordingly, these relays remain operated during impulsion.

When the wiper shaft 171 of the switching mechanism 170 is driven one step in the vertical direction the set of switch springs S180 is actuated into engagement, thereby to prepare a circuit traced hereinafter for energizing the winding of the step relay R150; and the set of switch springs S181 is actuated into engagement, thereby to prepare a circuit traced hereinafter for energizing the release magnet M179. Upon operating, the transfer relay R140 completes, at the contacts 141, the previously mentioned circuit for energizing the winding of the step relay R150, this circuit extending from ground by way of the contacts 131 and 141, the sets of switch springs S180 and S183 and the winding of R150 to battery. When thus energized the step relay R150 operates to prepare, at the contacts 151, a circuit traced hereinafter for energizing the rotary magnet M177. Also, the step relay R150 completes, at the contacts 152, a path for short-circuiting the winding of the switch-through relay R110, thereby positively to prevent operation of the latter relay at this time. The path mentioned extends from ground by way of the contacts 117 and 152, the winding of R110, the switch springs 190 and 189 of the set of switch springs S188, the control conductor C108 of the trunk 105 and the contacts 131 to ground.

In the present example, at the conclusion of the prefix digit 2, the wiper shaft 171 occupies its second vertical step, whereupon the set of switch springs S183 is actuated into disengagement and the set of switch springs S182 is actuated into engagement, the sets of switch springs S182 and S183 being actuated in the manner mentioned only when the wiper shaft 171 of the switching mechanism 170 is driven two steps in the vertical direction. When the set of switch springs S183 is thus actuated into disengagement the previously traced circuit for energizing the winding of the step relay R150 is interrupted, thereby to cause the latter relay to restore. Upon restoring, the step relay R150 interrupts, at the contacts 151, a point in the previously mentioned prepared circuit for energizing the rotary magnet M177, and interrupts, at the contacts 152, the previously traced path for short-circuiting the winding of the switch-through relay R110. When the set of switch springs S182 is actuated into engagement a circuit traced hereinafter is prepared for energizing the release magnet M179.

At the conclusion of the prefix digit 2, the line relay R120 retains its operated position, thereby to retain operated the hold relay R130; and shortly thereafter the transfer relay R140 restores, the latter relay being of the slow-to-release type, as previously noted. Upon restoring, the transfer relay R140 interrupts, at the contacts 141, a further point in the previously traced circuit for energizing the winding of the step relay R150, and completes, at the contacts 142, the previously mentioned circuit for energizing the release magnet M179. The last-mentioned circuit extends from ground by way of the contacts 131 and 142, the set of switch springs S182, the contacts 168 and the release magnet M179 to battery. When thus energized the release magnet M179 operates to release the

switching mechanism 170, thereby to cause the wiper shaft 171 to be returned to its normal vertical position. Also, upon restoring, the transfer relay R140 completes, at the contacts 142, a multiple circuit for energizing the lower winding of the prefix relay R160, this circuit extending from ground by way of the contacts 131 and 142, the set of switch springs S182, the contacts 168, 166 and 132 and the lower winding of R160 to battery. When thus energized the prefix relay R160 operates one step in order to complete, at the contacts 165 thereof, an obvious path, including the grounded control conductor C108 of the trunk 105, for short-circuiting the upper winding thereof.

When the switching mechanism 170 is released and the wiper shaft 171 is returned to its normal vertical position, in the manner previously explained, the set of switch springs S183 is again actuated into engagement and the set of switch springs S182 is again actuated into disengagement. When the set of switch springs S182 is actuated into disengagement the previously traced circuit for energizing the lower winding of the prefix relay R160 and the previously mentioned path for short-circuiting the upper winding of the prefix relay R160 are interrupted, whereupon an obvious circuit, including the grounded control conductor C108 of the trunk 105, is completed for energizing in series the upper and lower windings of the prefix relay R160. When the prefix relay R160 is thus energized it takes a second step or operates fully in order to interrupt, at the contacts 162, a further common point in the previously traced circuit for energizing the release magnet M179 and the lower winding thereof. Also, the prefix relay R160 interrupts, at the contacts 166, a further point in the previously traced original circuit for energizing the lower winding thereof and the previously mentioned path for short-circuiting the upper winding thereof. Also, the prefix relay R160 interrupts, at the contacts 161, the connection of ground potential to the switch spring 185 of the set of switch springs S184, and completes, at the contacts 162, a connection between the test wiper 174 of the wiper set carried by the wiper shaft 171 and the switch spring 185 of the set of switch springs S184. Finally, the prefix relay R160 interrupts, at the contacts 163, the normally completed connection between the test wiper 174 and the switch spring 187 of the set of switch springs S184, and completes, at the contacts 164, an obvious connection between the switch spring 193 of the set of switch springs S184 and the switch spring 187 of the set of switch springs S184. Accordingly, at this time, the test wiper 174 is connected by way of the contacts 162, the switch springs 185 and 189 of the set of switch springs S184, the test conductor C125, the contacts 115, the winding of the switch-through relay R110 and the switch springs 190 and 189 of the set of switch springs S188 to the grounded control conductor C108 of the trunk 105, for a purpose more fully explained herein-after. Further, it is noted that when the switching mechanism 170 is released and the wiper shaft 171 is returned to its normal vertical position the sets of switch springs S180 and S181 are actuated into disengagement.

The subscriber at the calling subscriber sub-station "T" then proceeds to dial the second digit 0, thereby to cause the line relay R120 to follow the impulses of the digit mentioned, in the manner previously explained. At the beginning of

the second digit 0 the transfer relay R140 re-operates; the hold relay R130 and the transfer relay R140 being retained operated during the second digit. Upon operating, the transfer relay R140 completes, at the contacts 141, an alternative circuit for energizing the winding of the step relay R150, this circuit extending from ground by way of the contacts 131 and 141, the set of switch springs S180, the contacts 167 and 10 the winding of R150 to battery. When thus energized the step relay R150 re-operates in order to prepare, at the contacts 151, the previously mentioned circuit for energizing the rotary magnet M177, and to complete, at the contacts 152, the previously traced path for short-circuiting the winding of the switch-through relay R110. At this point, it is again noted that the sets of switch springs S180 and S181 are each actuated into engagement when the wiper shaft 171 of the switching mechanism 170 is driven one step in the vertical direction.

At the conclusion of the second digit 0, the wiper shaft 171 of the switching mechanism 170 occupies its tenth vertical step, thereby to bring the lower cam 310 carried thereby into cooperative relationship with respect to the roller 314 carried by the switch spring 186 of the set of switch springs S184, in the manner explained in conjunction with Figs. 3 to 6, inclusive, of the drawings. Shortly following the conclusion of the second digit 0 the transfer relay R140 restores, thereby to complete, at the contacts 142, the previously mentioned circuit for energizing the rotary magnet M177, this circuit extending from ground by way of the contacts 131 and 142, the rotary magnet M177 and the contacts 151 to battery. When thus energized the rotary magnet M177 operates to drive the wiper shaft 171 one step in the rotary clockwise direction, in the manner previously explained, and to interrupt, at the contacts 178, a further point in an alternative circuit traced hereinafter for energizing the winding of the step relay R150. Also, the transfer relay R140 interrupts, at the contacts 141, the previously traced original circuit for energizing the winding of the step relay R150, thereby to cause the latter relay to restore. Upon restoring, the step relay R150 interrupts, at the contacts 151, the previously traced circuit for energizing the rotary magnet M177, thereby to cause the latter magnet to restore. Further, the step relay R150 interrupts, at the contacts 152, the previously traced path for short-circuiting the winding of the switch-through relay R110.

At this time, the wiper set carried by the wiper shaft 171 of the switching mechanism 170 engages the first contact set terminating the trunk 201 in the tenth level in the associated contact bank 176; and ground potential is connected by way of the contacts 131, the control conductor C108 of the trunk 105, the switch springs 189 and 190 of the set of switch springs S188, the winding of the switch-through relay R110, the contacts 115, the test conductor C125, the switch springs 186 and 185 of the set of switch springs S184 and the contacts 162 to the test wiper 174 of the wiper set mentioned; and the idle or busy condition of the trunk 201 is tested by the selector 100.

In the event the trunk 201 is busy at this time, ground potential appears upon the control conductor thereof and is applied to the test wiper 174, thereby to complete an obvious path substantially identical to that previously traced for short-circuiting the winding of the switch-through relay R110 in order positively to prevent

operation of the latter relay at this time. Also, the last-mentioned application of ground potential to the test wiper 174 completes a circuit, including the contacts 162, the switch springs 185 and 186 of the set of switch springs S184, the test conductor C125, the contacts 115 and 178, the set of switch springs S180 and the contacts 167, for energizing the winding of the step relay R150. When the step relay R150 is thus energized it operates in order to complete, at the contacts 151, the previously traced circuit for energizing the rotary magnet M177, whereupon the latter magnet operates in order to drive the wiper shaft 171 an additional step in the rotary clockwise direction. Further, the step relay R150 completes, at the contacts 152, the previously traced path for short-circuiting the winding of the switch-through relay R110 in order positively to prevent the latter relay from operating at this time. Also, upon operating, the rotary magnet M177 interrupts, at the contacts 178, the previously traced circuit, including the test wiper 174, for energizing the winding of the step relay R150, thereby to cause the latter relay to restore. Upon restoring, the step relay R150 interrupts, at the contacts 151, the previously traced circuit for energizing the rotary magnet M177 in order to cause the latter magnet to restore. Also, the step relay R150 interrupts, at the contacts 152, the previously traced path for short-circuiting the winding of the switch-through relay R110. At this time, the wiper set carried by the wiper shaft 171 engages the second contact set in the tenth level in the associated contact bank 175 and the trunk terminated by the last-mentioned wiper set is tested, in the manner explained above. The repeated testing of the various trunks terminated by the contact sets in the tenth level in the contact bank 175 proceeds, in the manner explained above, until a contact set in the tenth level in the contact bank 175 terminating an idle trunk is tested.

Assuming that the trunk 207 terminated by the seventh contact set in the tenth level in the contact bank 175 is the first idle trunk in the associated group of seven trunks, the wiper shaft 171 of the switching mechanism 170 is driven in the rotary clockwise direction, step by step, seven steps, whereupon the wiper set carried by the wiper shaft 171 engages the seventh contact set in the tenth level in the associated contact bank 175. At this time, the trunk 207 is marked as idle by the presence of battery potential upon the control conductor thereof, which battery potential is applied to the test wiper 174. The application of battery potential to the test wiper 174 completes a path, including the contacts 162, the switch springs 185 and 186 of the set of switch springs S184, the test conductor C125, the contacts 115 and 178, the set of switch springs S180 and the contacts 167, for short-circuiting the winding of the step relay R150, thereby positively to prevent further operation thereof and the consequent further operation of the wiper shaft 171 of the switching mechanism 170 in the rotary clockwise direction. Also, the application of battery potential to the test wiper 174 completes a circuit, including the contacts 162, the switch springs 185 and 186 of the set of switch springs S184, the test conductor C125, the contacts 115, the switch springs 190 and 189 of the set of switch springs S188, the control conductor C108 of the trunk 105 and the contacts 131, for energizing the winding of the switch-through relay R110.

When thus energized the switch-through relay 75

R110 operates to interrupt, at the contacts 115, the previously traced path for short-circuiting the winding of the step relay R150, and to complete, at the contacts 116, a path, including the contacts 131, the test conductor C125, the switch springs 186 and 185 of the set of switch springs S184 and the contacts 162, for applying direct ground potential to the test wiper 174. The application of direct ground potential to the test wiper 174 causes operation of the connector 232 terminating the trunk 207, the trunk 207 being terminated by the seized seventh contact set in the tenth level in the contact bank 175 of the switching mechanism 170, as previously explained. More particularly, the connector 232 operates in order to return ground potential over the control conductor of the trunk 207 and consequently over the test wiper 174. When ground potential is thus returned over the test wiper 174 a holding circuit is completed for energizing in series the winding of the switch-through relay R110 and the winding of the step relay R150, this circuit extending from the grounded test wiper 174 by way of the contacts 162, the switch springs 185 and 186 of the set of switch springs S184, the test conductor C125, the contacts 116, the control conductor C108 of the trunk 105, the switch springs 189 and 190 of the set of switch springs S188, the winding of R110, the contacts 178, the set of switch springs S180, the contacts 167 and the winding of R150 to battery. When this series holding circuit is completed the switch-through relay R110 is retained in its operated position; however, the step relay R150 does not operate due to the high series resistance of the winding of the switch-through relay R110.

Also, upon operating, the switch-through relay R110 interrupts, at the contacts 117, the previously traced circuit for energizing the winding of the hold relay R130, thereby to cause the latter relay to restore shortly thereafter, the hold relay R130 being of the slow-to-release type, as previously noted. Upon restoring, the hold relay R130 interrupts, at the contacts 131, the previously traced path for applying ground potential in the selector 100 to the control conductor C108 of the trunk 105. However, at this time, ground potential is applied to the control conductor C108 of the trunk 105 by way of the previously traced circuit, including the test wiper 174, from the connector 232. Hence, the selector 100 and the line switch 102 are retained in their operated positions and the marking of the subscriber line 101 as busy to the connectors having access thereto is retained. Further, the switch-through relay R110 interrupts, at the contacts 111 and 113, the previously traced loop circuit extending between the calling subscriber substation T1 and the line relay R120 in the selector 100, thereby to deenergize the upper and lower windings of the line relay R120 in order to cause the latter relay to restore. Finally, the switch-through relay R110 completes, at the contacts 112 and 114, a loop circuit extending between the calling subscriber substation T1 and the connector 232. This loop circuit extends from the line conductor C106 of the trunk 105 by way of the contacts 112 and the line wiper 172 to one of the line conductors of the trunk 207, and from the line conductor C107 of the trunk 105 by way of the contacts 114 and the line wiper 173 to the other line conductor of the trunk 207; the line conductors C106 and C107 of the trunk 105 being

connected together at the calling subscriber substation T1 by way of the line switch 102 and the subscriber line 101, and the line conductors of the trunk 207 being connected to ground and battery potentials in the connector 232. At this time, the connector 232 is in readiness to receive the last two digits XX.

The subscriber at the calling subscriber substation T1 then proceeds to dial the last two digits XX, which digits are transmitted over the previously traced loop circuit to the connector 232 in order to cause the last-mentioned connector to operate in a well-known manner to seize the subscriber line 230 extending to the called subscriber substation T2. The subsequent operation of the connector 232 depends upon the idle or busy condition of the called subscriber substation T2, in accordance with conventional practice. In the event the called subscriber substation T2 is busy at this time, the connector 232 operates in order to cause busy tone current to be returned over the trunk 207, the selector 109, the trunk 105, the line switch 102 and the subscriber line 101 to the calling subscriber substation T1; whereupon the subscriber at the calling subscriber substation T1 releases the connection by replacing the receiver of the telephone instrument thereat upon its associated switchhook. On the other hand, in the event the called subscriber substation T2 is idle at this time, the connector 232 operates in order to cause ringing current to be projected over the subscriber line 230, and to cause ring-back tone current to be returned over the trunk 207, the selector 109, the trunk 105, the line switch 102 and the subscriber line 101 to the calling subscriber substation T1. In this event, after the subscriber at the called subscriber substation T2 answers the call by removing the receiver of the telephone instrument thereat from its associated switchhook, the connector 232 operates in order to complete an obvious connection between the calling subscriber substation T1 and the called subscriber substation T2, this connection including the subscriber line 101, the line switch 102, the trunk 105, the selector 109, the trunk 207, the connector 232 and the subscriber line 230. Also, it is noted that, when the connector 232 operates to seize the subscriber line 230 extending to the called subscriber substation T2, ground potential is applied to the control conductor thereof, thereby to mark the subscriber line 230 as busy to the other connectors having access thereto.

The release of this established connection is primarily under the control of the subscriber at the calling subscriber substation T1 and is effective when the subscriber at the calling subscriber substation T1 replaces the receiver of the telephone instrument thereat upon its associated switchhook in order to interrupt the previously traced loop circuit extending between the calling subscriber substation T1 and the connector 232. When the loop circuit mentioned is thus interrupted the connector 232 is released in order to interrupt the application of ground potential to the control conductor of the trunk 207 extending thereto. When ground potential is thus removed from the control conductor of the trunk 207 and consequently from the test wiper 174 and the control conductor C108 of the trunk 105, the line switch 102 is released, whereupon the subscriber line 101 extending to the calling subscriber substation T1 is marked as idle to the connectors having access thereto. Further, when ground

potential is removed from the control conductor C108 of the trunk 105 the previously traced holding circuit for energizing in series the winding of the switch-through relay R110 and the winding of the step relay R150 is interrupted, thereby to cause the switch-through relay R110 to restore. Upon restoring, the switch-through relay R110 completes, at the contacts 117, an obvious circuit, including the contacts 122 and 134, and the set of switch springs S181, for energizing the release magnet M179. When the release magnet M179 is thus energized it operates to release the switching mechanism 170, whereby the wiper shaft 171 is returned first to its normal rotary position and then to its normal vertical position. When the switching mechanism 170 is thus released, each of the sets of switch springs S180 and S181 is actuated into disengagement, the previously traced circuit for energizing the release magnet M179 being interrupted when the set of switch springs S181 is actuated into disengagement. Finally, it is noted that when ground potential is removed from the control conductor C108 of the trunk 105 the previously traced holding circuit for energizing in series the upper and lower windings of the prefix relay R160 is interrupted, thereby to cause the latter relay to restore. At this time, the selector 109 is completely released.

Further, it is noted that when the connector 232 is released the subscriber line 230 is marked as idle to the other connectors having access thereto, assuming that the subscriber at the called subscriber substation T2 has replaced the receiver of the telephone instrument thereat upon its associated switchhook at this time. Accordingly, at this time, the established connection between the calling subscriber substation T1 and the called subscriber substation T2 is completely released and the apparatus previously employed therein is available for further use.

In the foregoing explanation of the mode of operation of the selector 109 incident to the extension of a call from the calling subscriber substation T1 to the called subscriber substation T2, it was assumed that there was an idle trunk in the group of seven terminated by the first seven contact sets in the tenth level in the contact bank 175 of the switching mechanism 170 and extending to the various connectors, including the connector 232; however, it may occur that there is no idle trunk in the group mentioned incident to operation of the selector 109 in response to the second digit 0 after the prefix digit 2 has been dialed, in the manner explained above. In this event, after the selector 109 responds to the second digit 0, in the manner explained above, operation thereof is initiated to test the various trunks in the group mentioned, in the manner previously explained. However, in this event, there is no idle trunk in the group mentioned; accordingly, the wiper shaft 171 is driven step by step in the rotary clockwise direction past the seventh step and into the eighth step thereof away from its normal rotary position.

At this point, it is noted that the lower cam 310 carried by the wiper shaft 171 and positioned adjacent the roller 314 is so adjusted that when the wiper shaft 171 is driven eight steps in the rotary clockwise direction the second cam surface 318 of the lower cam 310 operates the roller 314 carried by the switch spring 186, whereupon the switch springs 186 and 185 of the set of switch springs S184 are actuated into disengagement and the switch springs 186 and 187 of the set of switch springs S184 are actuated into engage-

ment. Hence, at this time, the test conductor C125 is disconnected from the test wiper 174 and is connected to the set of switch springs S191; whereupon direct ground potential is applied by way of the switch springs 192 and 193 of the set of switch springs S191, the contacts 164, and the switch springs 187 and 186 of the set of switch springs S184 to the test conductor C125. Accordingly, it will be understood that, when the wiper set carried by the wiper shaft 171 is rotated to engage the eighth contact set in the tenth level in the contact bank 175, the set of switch springs S184 is actuated, whereby there is no testing of the last three trunks in the group, including the trunks 208 and 209, terminated by the last three contact sets in the tenth level in the contact bank 175 and extending to the manual operator position 0. Hence, at this time, the step relay R150 and the rotary magnet M177 interact, in the manner previously explained, whereby the wiper shaft 171 of the switching mechanism 170 is automatically driven step by step eleven steps away from its normal rotary position.

When the wiper shaft 171 of the switching mechanism 170 is driven eleven steps away from its normal rotary position the cam surface 319 provided on the bracket 303 engages the roller 314 carried by the switch spring 186, thereby to effect operation of the sets of switch springs S188, S191 and S194, in the manner explained in conjunction with Figs. 3 to 6, inclusive, of the drawings. More particularly, the switch springs 189 and 190 of the set of switch springs S188 are actuated into disengagement, thereby to interrupt a point in the connection between the control conductor C108 of the trunk 105 and the winding of the switch-through relay R110. This arrangement positively prevents operation of the switch-through relay R110 when the switch springs 192 and 193 of the set of switch springs S191 are actuated into disengagement. Also, the switch springs 192 and 193 of the set of switch springs S191 are actuated into disengagement, thereby to interrupt the previously traced circuit for energizing the winding of the step relay R150 in order to cause the latter relay to restore, thereby to prevent further operation of the rotary magnet M177. Also, the switch springs 196 and 197 of the set of switch springs S194 are actuated into disengagement, and the switch springs 195 and 196 of the set of switch springs S194 are actuated into engagement; whereupon an obvious alternative loop circuit, including the busy tone conductor C103, is completed between the calling subscriber substation T1 and the line relay R120 in the selector 100. When this alternative loop circuit is completed, busy tone current is returned from the selector 100 over the trunk 105, the line switch 102 and the subscriber line 101 to the calling subscriber substation T1, thereby to indicate to the subscriber at the calling subscriber substation T1 that the desired connection may not be had immediately due to the all-busy condition of the trunks in the desired group appearing before the selector 100, as explained above. The subscriber at the calling subscriber substation T1 then proceeds to release the selector 100 and the line switch 102 by replacing the receiver of the telephone instrument at the calling subscriber substation T1 upon its associated switchhook, in the manner previously explained.

In view of the foregoing explanation of the mode of operation of the selector 100 to extend a call from the calling subscriber substation T1 to the called subscriber substation T2, it will be 75

understood that a call may be extended from any calling subscriber substation to any called subscriber substation, in a substantially identical manner, by the selector 100 and an idle connector in the appropriate group in response to the prefix digit 2 and the digits YXX, wherein the digit Y represents the ten groups of connectors and the digits XX represent the vertical and rotary positions of the called subscriber line before 10 the various connectors in the desired group. In this connection, it is pointed out that, in the event the directory number of the called subscriber substation comprises the digits 21XX, the operation of the selector 100 is substantially 15 identical to that explained above, except that the upper cam 310 carried by the wiper shaft 171 is utilized to operate the set of switch springs S184 in this case. Also, in this case, the upper cam 310 is adjusted with respect to the wiper shaft 171 so that the roller 314 carried by the switch spring 186 is actuated thereby when the wiper shaft 171 is moved six steps in the rotary clockwise direction away from its normal rotary position after it has been previously moved one step 20 in the vertical direction away from its normal vertical position. This arrangement positively insures that the trunks in the group, including the trunks 216 and 210, terminated by the last five contact sets in the first level in the contact 25 bank 175 of the switching mechanism 170 and extending to the group of special service selectors, are not tested by the selector 100, in the example mentioned.

Considering now the extension of a call from 30 a subscriber substation, such, for example, as the subscriber substation T1, to the manual operator position 0, the call is first initiated at the calling subscriber substation T1, in the manner previously explained. Again assuming that the 35 line switch 102 individually connected to the subscriber line 101 extending to the calling subscriber substation T1 is operated to seize the trunk 105 extending to the selector 100, the previously traced loop circuit extending between the 40 calling subscriber substation T1 and the line relay R120 in the selector 100 is again completed.

The subscriber at the calling subscriber substation T1 then proceeds to dial the single digit 0, thereby to cause the line relay R120 in the selector 100 to follow the impulses of the digit mentioned. At this time, both the hold relay R130 and the transfer relay R140 occupy their operated positions and the vertical magnet M176 is energized and deenergized ten times, in the manner previously explained; whereupon the wiper shaft 171 is driven ten steps in the vertical direction away from its normal vertical position. At the conclusion of the digit 0, the step relay R150 occupies its operated position, thereby to retain prepared, at the contacts 151, the previously traced circuit for energizing the rotary magnet M177, and to retain completed, at the contacts 152, the previously traced path for short-circuiting the winding of the switch-through relay R110. Also, at this time, each of the sets of switch springs S180 and S181 is actuated into engagement.

Shortly following the conclusion of the digit 0 the transfer relay R140 restores, this relay being of the slow-to-release type, as previously noted. Upon restoring, the transfer relay R140 completes, at the contacts 142, the previously traced circuit for energizing the rotary magnet M177, thereby to cause the rotary magnet M177 to operate and drive the wiper shaft 171 one step in the

rotary clockwise direction away from its normal rotary position. Also, the transfer relay R140 interrupts, at the contacts 141, the previously traced circuit for energizing the winding of the step relay R150, thereby to cause the latter relay to restore. Upon restoring, the step relay R150 interrupts, at the contacts 151, the previously traced circuit for energizing the rotary magnet M177, thereby to cause the rotary magnet M177 to restore. Upon restoring, the rotary magnet M177 completes a direct ground circuit for energizing the winding of the step relay R150, this circuit extending from ground by way of the contacts 161, the switch springs 185 and 186 of the set of switch springs S184, the test conductor C125, the contacts 115 and 116, the sets of switch springs S180 and S163 and the winding of R150 to battery. When thus energized the step relay R150 reoperates. In the present example, the step relay R150 and the rotary magnet M177 interact in the manner explained above, thereby to cause the wiper shaft 171 to be driven automatically step by step in the rotary clockwise direction eight steps away from its normal rotary position. It is again noted that, when the wiper shaft 171 of the switching mechanism 170 is driven eight steps in the rotary clockwise direction away from its normal rotary position, the lower cam 310 carried by the wiper shaft 171 operates the roller 314 carried by the switch spring 186; whereupon the switch springs 185 and 186 of the set of switch springs S184 are actuated into disengagement and the switch springs 187 and 188 of the set of switch springs S184 are actuated into engagement. Also, at this time, the wiper set carried by the wiper shaft 171 engages the eighth contact set in the tenth level in the associated contact bank 175 terminating the trunk 208 extending to the manual operator position 0. At this time, the test wiper 174 is connected by way of the contacts 163, the switch springs 187 and 188 of the set of switch springs S184, the test conductor C125 and the contacts 115 to the winding of the switch-through relay R110. Accordingly, the idle or busy condition of the trunk 208 extending to the manual operator position 0 is tested, in the manner previously explained.

In view of the foregoing explanation of the mode of operation of the selector 100 in response to the single digit 0, it will be understood that the wiper set carried by the wiper shaft 171 of the switching mechanism 170 is automatically driven in the rotary clockwise direction over the first seven contact sets in the tenth level in the associated contact bank 175 without testing the trunks terminated by the contact sets mentioned; and that the trunks terminated by the last three contact sets in the tenth level in the associated contact bank 175 are then progressively tested, in the manner previously explained. This arrangement positively insures that the selector 100 will not respond to the digit 0 and select an idle trunk in the group, including the trunks 201 and 207, extending to the various connectors in the tenth group.

As previously explained, when the wiper set carried by the wiper shaft 171 of the switching mechanism 170 engages the eighth contact set in the tenth level in the associated contact bank 175 the trunk 208 extending to the manual operator position 0 is tested by the selector 100; and further operation of the switching mechanism 170 is effected only in the event the trunk 208 is tested as busy, in the manner previously ex-

plained. Assuming that the trunk 200 terminated by the tenth contact set in the tenth level in the contact bank 175 is the first idle trunk in the group of three extending to the manual operator position 0, further operation of the switching mechanism 170 is effected in order to cause the wiper shaft 171 to be driven ten steps in the rotary clockwise direction away from its normal rotary position. At this time, the wiper set carried by the wiper shaft 171 engages the tenth contact set in the tenth level in the associated contact bank 175 terminating the idle trunk 200, thereby to cause the selector 100 to switch through, in the manner previously explained. At this time, the call is extended from the calling subscriber substation T1 to the manual operator position 0 by way of the subscriber line 101, the line switch 102, the trunk 105, the selector 100 and the trunk 200. At this point, it is noted that the trunk circuit associated with the trunk 200 operates when the last-mentioned trunk is seized by the selector 100 in order to cause ground potential to be returned over the control conductor thereof to the test wiper 174. This application of ground potential to the test wiper 174 retains the selector 100 and the line switch 102 in their operated positions and retains the subscriber line 101 marked as busy to the connectors having access thereto, in the manner previously explained. Further, when the trunk 200 is thus seized by the selector 100 a signal at the manual operator position 0 is operated in order to indicate to the operator thereat that this trunk has been seized. The operator at the manual operator position 0 then answers the call, thereby to complete the previously traced established connection. The release of this established connection between the calling subscriber substation T1 and the manual operator position 0 is primarily under the control of the subscriber at the calling subscriber substation T1 and is effected, in the manner previously explained, when the subscriber at the calling subscriber substation T1 replaces the receiver of the telephone instrument thereat upon its associated switchhook.

In the foregoing explanation of the mode of operation of the selector 100 incident to the extension of a call from the calling subscriber substation T1 to the called manual operator position 0, it was assumed that there was an idle trunk in the group of three terminated by the last three contact sets in the tenth level in the contact bank 175 of the switching mechanism 170 and extending to the manual operator position 0; however, it may occur that there is no idle trunk in the group mentioned incident to operation of the selector 100 in response to the single digit 0. In this event, the wiper shaft 171 of the switching mechanism 170 is driven eleven steps in the rotary clockwise direction, whereupon the bracket 303 carried thereby operates the roller 314 carried by the switch spring 186 in order to actuate the sets of switch springs S189, S191 and S194, in the manner previously explained. When the set of switch springs S194 is thus actuated, busy tone current is returned over the loop circuit extending between the calling subscriber substation T1 and the line relay R120 in the selector 100, in the manner previously noted; whereupon the subscriber at the calling subscriber substation T1 effects the release of the line switch 102 and the selector 100 by replacing the receiver of the telephone instrument thereat upon its associated switchhook, in the manner previously explained.

Considering now the extension of a call from

a subscriber substation, such, for example, as the subscriber substation T1, to the toll operator position 110, the call is first initiated at the calling subscriber substation T1, in the manner previously explained. Again assuming that the line switch 102 individually connected to the subscriber line 101 extending to the calling subscriber substation T1 is operated to seize the trunk 105 extending to the selector 100, the previously traced loop circuit extending between the calling subscriber substation T1 and the line relay R120 in the selector 100 is again completed.

The subscriber at the calling subscriber substation T1 then proceeds to dial the digits 110, thereby to cause the line relay R120 in the selector 100 to follow the first digit 1. At this time, both the hold relay R130 and the transfer relay R140 occupy their operated positions and the vertical magnet M176 is energized and deenergized once, in the manner previously explained; whereupon the wiper shaft 171 is driven one step in the vertical direction away from its normal vertical position. At the conclusion of the first digit 1, the step relay R150 occupies its operated position, thereby to retain prepared, at the contacts 151, the previously traced circuit for energizing the rotary magnet M177, and to retain completed, at the contacts 152, the previously traced path for short-circuiting the winding of the switch-through relay R110. Also, at this time, each of the sets of switch springs S180 and S181 is actuated into engagement.

Shortly following the conclusion of the first digit 1, the transfer relay R140 restores, this relay being of the slow-to-release type, as previously noted. Upon restoring, the transfer relay R140 completes, at the contacts 142, the previously traced circuit for energizing the rotary magnet M177, thereby to cause the rotary magnet M177 to operate and drive the wiper shaft 171 one step in the rotary clockwise direction away from its normal rotary position. Also, the transfer relay R140 interrupts, at the contacts 141, the previously traced circuit for energizing the winding of the step relay R150, thereby to cause the latter relay to restore. Upon restoring, the step relay R150 interrupts, at the contacts 151, the previously traced circuit for energizing the rotary magnet M177, thereby to cause the rotary magnet M177 to restore. Upon restoring, the rotary magnet M177 completes a direct ground circuit for energizing the winding of the step relay R150, this circuit extending from ground by way of the contacts 161, the switch springs 185 and 186 of the set of switch springs S184, the test conductor C125, the contacts 115 and 178, the sets of switch springs S189 and S183 and the winding of R150 to battery. When thus energized the step relay R150 reoperates. In the present example, the step relay R150 and the rotary magnet M177 interact in the manner explained above, thereby to cause the wiper shaft 171 to be driven automatically step by step in the rotary clockwise direction six steps away from its normal rotary position. It is again noted that, when the wiper shaft 171 of the switching mechanism 170 is driven six steps in the rotary clockwise direction away from its normal rotary position, the upper cam 310 carried by the wiper shaft 171 operates the roller 314 carried by the switch spring 186, whereupon the switch springs 185 and 186 of the set of switch springs S184 are actuated into disengagement and the switch springs 186 and 187 of the set of switch springs S184 are actuated into en-

gagement. Also, at this time, the wiper set carried by the wiper shaft 171 engages the sixth contact set in the first level in the associated contact bank 175 terminating the trunk 216 extending to the special service selector 233. At this time, the test wiper 174 is connected by way of the contacts 163, the switch springs 187 and 186 of the set of switch springs S184, the test conductor C125 and the contacts 115 to the winding of the switch-through relay R110. Accordingly, the idle or busy condition of the trunk 216 extending to the special service selector 233 is tested, in the manner previously explained.

In view of the foregoing explanation of the mode of operation of the selector 100 in response to the first digit 1, it will be understood that the wiper set carried by the wiper shaft 171 of the switching mechanism 170 is automatically driven in the rotary clockwise direction over the first five contact sets in the first level in the associated contact bank 175 without testing the trunks terminated by the contact sets mentioned; and that the trunks terminated by the last five contact sets in the first level in the associated contact bank 175 are then progressively tested, in the manner previously explained. This arrangement positively insures that the selector 100 will not respond to the first digit 1 and select an idle trunk in the group, including the trunks 211 and 215, extending to the various connectors in the first group.

As previously explained, when the wiper set carried by the wiper shaft 171 of the switching mechanism 170 engages the sixth contact set in the first level in the associated contact bank 175, the trunk 216 extending to the special service selector 233 is tested by the selector 100; and further operation of the switching mechanism 170 is effected only in the event the trunk 216 is tested as busy, in the manner previously explained. Assuming that the trunk 216 terminated by the sixth contact set in the first level in the contact bank 175 is the first idle trunk in the group of five extending to the special service selector 233, etc., no further operation of the switching mechanism 170 is effected. At this time, the call is extended from the calling subscriber substation T1 to the special service selector 233 by way of the subscriber line 101, the line switch 102, the trunk 105, the selector 100 and the trunk 216. At this point, it is noted that the trunk circuit associated with the trunk 216 operates when the last-mentioned trunk is seized by the selector 100 in order to cause ground potential to be returned over the control conductor thereof to the test wiper 174. This application of ground potential to the test wiper 174 retains the selector 100 and the line switch 102 in their operated positions and retains the subscriber line 101 marked as busy to the connectors having access thereto, in the manner previously explained. Further, when the trunk 216 is thus seized by the selector 100 the special service selector 233 is rendered responsive to the second digit 1.

The special service selector 233 then responds to the second digit 1 and drops back in a well-known manner; at which time it is rendered responsive to the third digit 0. Finally, the special service selector 233 responds to the third digit 0 in order to hunt for an idle trunk in the group extending to the toll operator position 110. The subsequent operation of the special service selector 233 depends upon the idle or busy condition of the trunks in the group extending to the

toll operator position 110, in a well-known manner. Assuming that the trunk 234 in the group mentioned is the first idle trunk, the special service selector 233 operates to seize the trunk 234, whereupon a signal is transmitted thereover to the toll operator position 110 in order to indicate to the operator thereat that this trunk has been seized. The operator at the toll operator position 110 then answers the call, thereby to complete the previously traced established connection. The release of this established connection between the calling subscriber substation T1 and the toll operator position 110 is primarily under the control of the subscriber at the calling subscriber substation T1 and is effected, in the manner previously explained, when the subscriber at the calling subscriber substation T1 replaces the receiver of the telephone instrument thereat upon its associated switchhook.

In view of the foregoing explanation of the mode of operation of the selector 100 and the special service selector 233 to extend a call from the calling subscriber substation T1 to the toll operator position 110 in response to the digits 110, it will be understood that this apparatus is operative, in a similar manner, in response to the digits 112 and 113, respectively, to extend a call from the calling subscriber substation T1 to the miscellaneous operator position 112 and the information operator position 113.

In the foregoing explanation of the mode of operation of the selector 100 incident to the extension of a call from the calling subscriber substation T1 to the called toll operator position 110, it was assumed that there was an idle trunk in the group of five terminated by the last five contact sets in the first level in the contact bank 175 of the switching mechanism 170 and extending to the special service selectors 233, etc.; however, it may occur that there is no idle trunk in the group mentioned incident to operation of the selector 100 in response to the first digit 1. In this event, the wiper shaft 171 of the switching mechanism 170 is driven eleven steps in the rotary clockwise direction, whereupon the bracket 303 carried thereby operates the roller 314 carried by the switch spring 186 in order to actuate the sets of switch springs S188, S191 and S194, in the manner previously explained. When the set of switch springs S194 is thus actuated, busy tone current is returned over the loop circuit extending between the calling subscriber substation T1 and the line relay R120 in the selector 100, in the manner previously noted; whereupon the subscriber at the calling subscriber substation T1 effects the release of the line switch 102 and the selector 100 by replacing the receiver of the telephone instrument thereat upon its associated switchhook, in the manner previously explained.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. In a signaling system, an automatic switch comprising a wiper set including two line wipers and a single test wiper, a terminal bank comprising terminal sets arranged in levels accessible to said wiper set, two groups of trunks terminated by the terminal sets in a given level of said bank, each of said trunks including two line conductors and a single test conductor, mechanism selectively operable to determine either one of said groups of trunks in said given level, means for initiating movement of said wiper set over the terminal sets in said given level, means governed by said mechanism for testing over said test wiper the test conductors of the trunks in the previously determined one of said groups, and means governed by said last-mentioned means for arresting movement of said wiper set, whereby said wiper set is controlled to select an idle trunk in said previously determined one of said groups.
2. In a signaling system, a line, an automatic switch associated with said line and comprising a wiper set including two line wipers and a single test wiper, a terminal bank comprising terminal sets arranged in levels accessible to said wiper set, two groups of trunks terminated by the terminal sets in a given level of said bank, each of said trunks including two line conductors and a single test conductor, mechanism operable to determine either one of said groups of trunks in said given level, means controllable over said line for selectively operating said mechanism, additional means controllable over said line for initiating movement of said wiper set over the terminal sets in said given level, means governed by said mechanism for testing over said test wiper the test conductors of the trunks in the previously determined one of said groups, and means governed by said last-mentioned means for arresting movement of said wiper set, whereby said wiper set is controlled to select an idle trunk in said previously determined one of said groups.
3. In a telephone system, a telephone station, a line extending to said station, an automatic switch comprising a wiper set including two line wipers and a single test wiper, means responsive to initiation of a call at said station for connecting said line to said switch, a terminal bank comprising terminal sets arranged in levels accessible to said wiper set, two groups of trunks terminated by the terminal sets in a given level of said bank, each of said trunks including two line conductors and a single test conductor, mechanism operable to determine either one of said groups of trunks in said given level, means controllable from said station over said line for selectively operating said mechanism, additional means controllable from said station over said line for initiating movement of said wiper set over the terminal sets in said given level, means governed by said mechanism for testing over said test wiper the test conductors of the trunks in the previously determined one of said groups, means governed by said last-mentioned means for arresting movement of said wiper set, whereby said wiper set is controlled to select an idle trunk in said previously determined one of said groups, and means responsive to the selection by said wiper set of said last-mentioned trunk for connecting said line to said wiper set.
4. In a signaling system, an automatic switch including a wiper, first and second groups of terminals accessible to said wiper, mechanism operable between two positions respectively corresponding to said first and second groups of terminals, means for selectively preparing either one of the positions of said mechanism, thereby to determine a corresponding one of said groups of terminals, a tester, means governed when said mechanism occupies a prepared one of its posi-

tions for rendering effective said tester, means for initiating movement of said wiper successively to engage the terminals in said first and second groups, means responsive to movement of said wiper over the terminals in said first group and into engagement with the first terminal in said second group for operating said mechanism from one of its positions to the other, whereby said mechanism is operated from a prepared position to an unprepared position or from an unprepared position to a prepared position, said tester being operative when it is rendered effective to test each terminal engaged by said wiper, and means controlled by said tester in response to the testing as idle of a terminal engaged by said wiper for arresting movement of said wiper, whereby said wiper is controlled to select an idle terminal in the previously determined one of said groups.

5. In a signaling system, an automatic switch including a wiper, first and second groups of terminals accessible to said wiper, a test conductor, mechanism operable between two positions respectively corresponding to said first and second groups of terminals, means for selectively preparing either one of the positions of said mechanism, thereby to determine a corresponding one of said groups of terminals, means controlled when said mechanism occupies a prepared one of its positions for connecting said test conductor to said wiper, means for initiating movement of said wiper successively to engage the terminals in said first and second groups, means responsive to movement of said wiper over the terminals in said first group and into engagement with the first terminal in said second group for operating said mechanism from one of its positions to the other, whereby said mechanism is operated from a prepared position to an unprepared position or from an unprepared position to a prepared position, and means controlled when said test conductor is connected to said wiper and in response to the engagement by said wiper of an idle terminal for arresting movement of said wiper, whereby said wiper is controlled to select an idle terminal in the previously determined one of said groups.

6. In a signaling system, an automatic switch including a wiper, first and second groups of terminals accessible to said wiper, a test conductor, mechanism operable between two positions respectively corresponding to said first and second groups of terminals, means for selectively preparing either one of the positions of said mechanism, thereby to determine a corresponding one of said groups of terminals, means controlled when said mechanism occupies a prepared one of its positions for connecting said test conductor to said wiper, means for initiating movement of said wiper successively to engage the terminals in said first and second groups, means responsive to movement of said wiper over the terminals in said first group and into engagement with the first terminal in said second group for operating said mechanism from one of its positions to the other, whereby said mechanism is operated from a prepared position to an unprepared position or from an unprepared position to a prepared position, means controlled when said test conductor is connected to said wiper and in response to the engagement by said wiper of an idle terminal for arresting movement of said wiper, whereby said wiper is controlled to select an idle terminal in the previously determined one of said groups, and additional means responsive to movement of said wiper over

the last terminal in said second group for arresting movement of said wiper.

7. In a signaling system, an automatic switch including a wiper, first and second groups of terminals accessible to said wiper, a test conductor, mechanism operable between two positions respectively corresponding to said first and second groups of terminals, means for selectively preparing either one of the positions of said mechanism, thereby to determine a corresponding one of said groups of terminals, means controlled when said mechanism occupies other than a prepared one of its positions for impressing a guard potential upon said test conductor, means for initiating movement of said wiper successively to engage the terminals in said first and second groups, means responsive to movement of said wiper over the terminals in said first group and into engagement with the first terminal in said second group for operating said mechanism from one of its positions to the other, whereby said mechanism is operated from a prepared position to an unprepared position or from an unprepared position to a prepared position, and means controlled jointly by the absence of said guard potential upon said test conductor and in response to the engagement by said wiper of an idle terminal for arresting movement of said wiper, whereby said wiper is controlled to select an idle terminal in the previously determined one of said groups.

8. In a signaling system, an automatic switch including a wiper, first and second groups of terminals accessible to said wiper, a test conductor, mechanism operable between two positions respectively corresponding to said first and second groups of terminals, means for selectively preparing either one of the positions of said mechanism, thereby to determine a corresponding one of said groups of terminals, means controlled when said mechanism occupies a prepared one of its positions for connecting said test conductor to said wiper and controlled when said mechanism occupies other than its prepared positions for impressing a guard potential upon said test conductor, means for initiating movement of said wiper successively to engage the terminals in said first and second groups, means responsive to movement of said wiper over the terminals in said first group and into engagement with the first terminal in said second group for operating said mechanism from one of its positions to the other, whereby said mechanism is operated from a prepared position to an unprepared position or from an unprepared position to a prepared position, additional means controlled when said test conductor is connected to said wiper and said wiper engages a busy terminal for impressing said guard potential upon said test conductor, and means responsive to the absence of said guard potential upon said test conductor for arresting movement of said wiper, whereby said wiper is controlled to select an idle terminal in the previously determined one of said groups.

65. 9. In a signaling system, a trunk, an automatic switch associated with said trunk and including a wiper, first and second groups of terminals accessible to said wiper, a test conductor, mechanism operable between two positions respectively corresponding to said first and second groups of terminals, means controllable over said trunk for selectively preparing either one of the positions of said mechanism, thereby to determine a corresponding one of said groups of terminals, means controlled when said mechanism

occupies a prepared one of its positions for connecting said test conductor to said wiper, additional means controllable over said trunk for initiating movement of said wiper successively to engage the terminals in said first and second groups, means responsive to movement of said wiper over the terminals in said first group and into engagement with the first terminal in said second group for operating said mechanism from one of its positions to the other, whereby said mechanism is operated from a prepared position to an unprepared position or from an unprepared position to a prepared position, and means controlled when said test conductor is connected to said wiper and in response to the engagement by said wiper of an idle terminal for arresting movement of said wiper, whereby said wiper is controlled to select an idle terminal in the previously determined one of said groups.

10. In a signaling system, a trunk, an automatic switch associated with said trunk and including a wiper, first and second groups of terminals accessible to said wiper, a test conductor, mechanism operable between two positions respectively corresponding to said first and second groups of terminals, means controllable over said trunk for selectively preparing either one of the positions of said mechanism, thereby to determine a corresponding one of said groups of terminals, means controlled when said mechanism occupies a prepared one of its positions for connecting said test conductor to said wiper, additional means controllable over said trunk for initiating movement of said wiper successively to engage the terminals in said first and second groups, means responsive to movement of said wiper over the terminals in said first group and into engagement with the first terminal in said second group for operating said mechanism from one of its positions to the other, whereby said mechanism is operated from a prepared position to an unprepared position or from an unprepared position to a prepared position, means controlled when said test conductor is connected to said wiper and in response to the engagement by said wiper of an idle terminal for arresting movement of said wiper, whereby said wiper is controlled to select an idle terminal in the previously determined one of said groups, and additional means responsive to movement of said wiper over the last terminal in said second group for arresting movement of said wiper and for impressing a busy signal upon said trunk.

11. In a signaling system, an automatic switch of the primary-secondary motion type including a wiper set having access to an associated terminal bank arranged in levels, first and second groups of trunks terminated in a given level of said bank, mechanism operable between two positions respectively corresponding to said first and second groups of trunks, means for selectively preparing either one of the positions of said mechanism, thereby to determine a corresponding one of said groups of trunks, means for imparting primary movement to said wiper set to said given level, means for initiating secondary movement of said wiper set in said given level successively to engage the trunks in said first and second groups, means responsive to secondary movement of said wiper set in said given level over said first group of trunks and into engagement with the first trunk in said second group of trunks for operating said mechanism from one of its positions to the other, whereby said mechanism is operated from a prepared position to an

unprepared position or from an unprepared position to a prepared position, and means controlled when said mechanism occupies its prepared position and in response to the engagement by said wiper set of an idle trunk for arresting secondary movement of said wiper set, whereby said wiper set is controlled to select an idle trunk in the previously determined one of said groups.

12. In a signaling system, an automatic switch of the primary-secondary motion type including a wiper set having access to an associated terminal bank arranged in levels, first and second groups of trunks terminated in a given level of said bank, mechanism operable between two positions respectively corresponding to said first and second groups of trunks, means for selectively preparing either one of the positions of said mechanism, thereby to determine a corresponding one of said groups of trunks, a tester, means governed when said mechanism occupies a prepared one of its positions for rendering effective said tester, means for imparting primary movement to said wiper set to said given level, means for initiating secondary movement of said wiper set in said given level successively to engage the trunks in said first and second groups, means responsive to secondary movement of said wiper set in said given level over said first group of trunks and into engagement with the first trunk in said second group of trunks for operating said mechanism from one of its positions to the other, whereby said mechanism is operated from a prepared position to an unprepared position or from an unprepared position to a prepared position, said tester being operative when it is rendered effective to test each trunk engaged by said wiper set, and means controlled by said tester in response to the testing as idle of a trunk engaged by said wiper set for arresting secondary movement of said wiper set, whereby said wiper set is controlled to select an idle trunk in the previously determined one of said groups.

13. In a signaling system, an automatic switch of the primary-secondary motion type including a wiper set having access to an associated terminal bank arranged in levels, first and second groups of trunks terminated in a given level of said bank, mechanism operable between two positions respectively corresponding to said first and second groups of trunks, one of the positions of said mechanism being normally prepared, thereby to determine the corresponding one of said groups of trunks, means responsive to a preliminary primary movement of said wiper set for releasing said wiper set and for preparing the other position of said mechanism, thereby to determine the corresponding other of said groups of trunks, a tester, means governed when said mechanism occupies a prepared one of its positions for rendering effective said tester, means for imparting primary movement to said wiper set to said given level, means for initiating secondary movement of said wiper set in said given level successively to engage the trunks in said first and second groups, means responsive to secondary movement of said wiper set in said given level over said first group of trunks and into engagement with the first trunk in said second group of trunks for operating said mechanism from one of its positions to the other, whereby said mechanism is operated from a prepared position to an unprepared position or from an unprepared position to a prepared position, said tester being operative when it is rendered effective to test each trunk engaged by said wiper

set, and means controlled by said tester in response to the testing as idle of a trunk engaged by said wiper set for arresting secondary movement of said wiper set, whereby said wiper set is controlled to select an idle trunk in the previously determined one of said groups.

14. In a signaling system, an automatic switch of the primary-secondary motion type including a wiper set having access to an associated terminal bank arranged in levels, first and second groups of trunks terminated in a given level of said bank, mechanism operable between two positions respectively corresponding to said first and second groups of trunks, a tester normally disconnected from said wiper set, thereby to determine said second group of trunks, means responsive to a preliminary primary movement of said wiper set for releasing said wiper set and for connecting said tester to said wiper set, thereby to determine said first group of trunks, means for imparting primary movement to said wiper set to said given level, means for initiating secondary movement of said wiper set in said given level successively to engage the trunks in said first and second groups, means responsive to secondary movement of said wiper set in said given level over said first group of trunks and into engagement with the first trunk in said second group of trunks for operating said mechanism from one of its positions to the other, means responsive to the last-mentioned operation of said mechanism for connecting said tester to said wiper set in the event it is disconnected therefrom and for disconnecting said tester from said wiper set in the event it is connected thereto, said tester being operative when it is connected to said wiper set to test each trunk engaged by said wiper set, and means controlled by said tester in response to the testing as idle of a trunk engaged by said wiper set for arresting secondary movement of said wiper set, whereby said wiper set is controlled to select an idle trunk in the previously determined one of said groups.

15. In a signaling system, an automatic switch of the primary-secondary motion type including a wiper set having access to an associated terminal bank arranged in levels, first and second groups of trunks terminated in a given level of said bank, a first contact set, means for selectively operating said first contact set, means for imparting primary movement to said wiper set to said given level, means for initiating secondary movement of said wiper set in said given level successively to engage the trunks in said first and second groups, a second contact set, means responsive to primary movement of said wiper set to said given level and subsequent secondary movement of said wiper set in said given level over said first group of trunks and into engagement with the first trunk in said second group of trunks for operating said second contact set, means controlled jointly by said first and second contact sets for governing the selectability of the trunks in said first and second groups, and means for arresting secondary movement of said wiper set in response to the engagement of an idle trunk in a selectable one of said groups, whereby said wiper set is controlled to select an idle trunk in a selectable one of said groups.

16. In a signaling system, an automatic switch including a shaft mounted for both longitudinal sliding and rotary movements, a wiper carried by said shaft, a stationary terminal bank accessible to said wiper and including a plurality of longitudinally spaced-apart rows of terminals arranged in circumferentially spaced-apart relation, a given one of said rows of terminals including first and second groups of terminals, a cam carried by said shaft, a stationary contact set associated with said cam, and means for imparting longitudinal sliding movement and then rotary movement to said shaft, said cam and said contact set being so constructed and arranged that said cam is moved adjacent said contact set when said shaft is moved longitudinally to bring said wiper into alignment with said given row of terminals and that said contact set is operated by said cam when said shaft is rotated to cause said wiper to engage the first terminal in said second group.

17. In a signaling system, an automatic switch including a shaft mounted for both longitudinal sliding and rotary movements, a wiper carried by said shaft, a stationary terminal bank accessible to said wiper and including a plurality of longitudinally spaced-apart rows of terminals arranged in circumferentially spaced-apart relation, a cam carried by said shaft, a stationary contact set associated with said cam, and means for imparting longitudinal sliding movement and then rotary movement to said shaft, the longitudinal position of said cam being adjustable with respect to said shaft, whereby said cam is moved adjacent said contact set when said shaft is moved longitudinally to bring said wiper into alignment with any predetermined row of terminals in said terminal bank, the rotary position of said cam being adjustable with respect to said shaft, whereby said cam operates said contact set when said shaft is rotated to cause said wiper to engage any predetermined terminal in said predetermined row of terminals in said terminal bank.

18. In a signaling system, an automatic switch including a shaft mounted for both longitudinal sliding and rotary movements, a wiper carried by said shaft, a stationary terminal bank accessible to said wiper and including a plurality of longitudinally spaced-apart rows of terminals arranged in circumferentially spaced-apart relation, a cam carried by said shaft, a stationary contact set associated with said cam, means for imparting longitudinal sliding movement and then rotary movement to said shaft, indicia carried by said shaft to facilitate adjustment of the longitudinal position of said cam with respect to said shaft, whereby said cam is moved adjacent said contact set when said shaft is moved longitudinally to bring said wiper into alignment with any predetermined row of terminals in said terminal bank, and indicia carried by said cam to facilitate adjustment of the rotary position thereof with respect to said shaft, whereby said cam operates said contact set when said shaft is rotated to cause said wiper to engage any predetermined terminal in said predetermined row of terminals in said terminal bank.

JOHN ELLIS OSTLINE.

DISCLAIMER

2,315,010.—*John Ellis Ostline, Chicago, Ill.* SIGNALING SYSTEM. Patent dated March 30, 1943. Disclaimer filed April 6, 1944, by the assignee, *Automatic Electric Laboratories, Inc.*

Hereby enters this disclaimer to claims 1, 2, and 3 of said Letters Patent.
